IDLER WHEEL FOR SNOWMOBILES OR THE LIKE

Raymont Morissette, 1649 Belvedere S.,
Sherbrooke, Quebec, Canada

Filed Oct. 15, 1969, Ser. No. 19,580

Term of patent 14 years

Int. Cl. D12—15

U.S. Cl. D14—30

FIG. 1

FIG. 2

FIG. 3

FIG. 5

FIG. 4

FIG. 1 is a perspective representation of the idler wheel for snowmobiles or the like as viewed from one side thereof;

FIG. 2 is a perspective representation of the aforesaid idler wheel for snowmobiles or the like from the opposite side to that shown in FIG. 1;

FIG. 3 is an elevation of the aforesaid wheel viewed from one side thereof;

FIG. 4 is a view similar to FIG. 3 but from the opposite side of said wheel; and

FIG. 5 is a side elevation of the aforesaid wheel.

I claim:

The ornamental design for an idler wheel for snowmobiles or the like, as shown.
